UNITED STATES PATENT OFFICE.

WILLIAM HARTY, OF PORTSMOUTH, OHIO.

METAL-HEATING FURNACE.

SPECIFICATION forming part of Letters Patent No. 316,963, dated May 5, 1885.

Application filed September 18, 1882. (No model.)

To all whom it may concern:

Be it known that I, WILLIAM HARTY, of 5
Portsmouth, in the county of Scioto and State
of Ohio, have invented certain new and use-
ful Improvements in Heating - Furnaces, of
which the following is a specification.

My invention relates to that class of furnaces
which are employed for heating iron or steel
preparatory to forming it into various shapes
10 or tempering, and is especially adapted to the
manufacture of steel springs, the bars of steel
being placed in the furnace and heated pre-
paratory to forming and tempering.

The object of my invention is to produce a
15 furnace by the employment of which the
greatest amount of heat may be obtained from
a given quantity of fuel, and whereby the stock
in the furnace is heated to an even degree
throughout, thus insuring an even temper in
20 all parts of the spring.

Referring to the drawings forming part of
this specification, Figure 1 represents a central
longitudinal section through the furnace.
Fig. 2 is a horizontal section taken at the line
25 *x x* of Fig. 1. Fig. 3 is a vertical transverse
section taken at the line *y y* of Fig. 1.

Z represents the front, and *Z'* the rear, of the
furnace.

A is the fire or fuel chamber, which is lo-
30 cated at the rear of the furnace, the door *a* of
which may be located in the rear wall, or,
preferably, as shown in the drawings, in the
side wall, the grate-bars running at right an-
gles to the length of the furnace. Below the
35 fire-chamber is the usual ash-pit, *A'*. In front
of the fire-chamber *A* is the heating-chamber
B, in which the stock to be heated is placed.
Both the roof and the floor of this heating-
chamber slant toward the front, as shown in
40 Fig. 1, to concentrate the heat in the heating-
chamber as the distance from the fire increases;
and the front opening is closed by a door, *b*,
either hinged, or, preferably, as shown in the
drawings, capable of sliding up and down, to
45 open or close the entrance to the heating-fur-
nace. When made to slide, a cord or chain is
usually attached to the upper edge of the door,
which, after passing over a pulley at the top
of the furnace, passes down and is attached
50 to a foot-lever by pressing down which the
door is raised, and both hands of the operator
are free to manipulate the stock.

Between the fire-chamber *A* and heating-
chamber *B* is a bridge-wall, *C*, between the
top of which and the roof of the furnace a 55
space or throat is left the height of which is
governed by the size of the furnace. On top
of this bridge-wall is placed an apron, *D*, ex-
tending from side to side of the furnace and
projecting into the heating-chamber *B*. The 60
greatest amount of heat in the heating-chamber
B is naturally nearest to the fire-chamber,
and diminishes gradually toward the opposite
end of the chamber, and the purpose of the
apron *D* is to equalize the heat throughout 65
the chamber, which it does by governing the
current of heated air and burning gases so
that they will be equally distributed by di-
recting them toward the front of the chamber,
at which point the exit-flues are located, thus 70
more perfectly compensating for the loss of
heat consequent upon the distance of the front
of the furnace away from the fire-chamber,
and by this means the stock is heated evenly
75 throughout. Were it not for this apron *D* the
burning gases from the fire-chamber, after
passing over the bridge-wall, would dip down
and strike the stock in the heating at a point
near the bridge-wall, and consequently this
80 end of the stock would be heated to a much
higher degree than the opposite end, near the
front of the chamber.

At either side of the front of the furnace
are the diving-flues *e*, which lead from the
heating-chamber *B* into the main exit-flue *E*, 85
located directly beneath the heating-chamber
and extending from the front to the rear end
of the furnace, at which latter point it opens
into a tunnel, *F*, leading to a stack, as shown
in Fig. 1, or directly into a stack, *F'*, as shown
90 in Fig. 2. Where the tunnel *F* is used, the
smoke from several furnaces may empty into
it and be conducted to a common stack. This
flue *E*, being located directly under the heat-
ing-chamber *B*, compels all the products of 95
combustion, after passing forward through the
heating-chamber *B*, to pass backward under
the floor of said chamber, which floor soon
becomes very hot, thereby adding greatly to
the heat in the heating-chamber, and any gases
100 which are unconsumed in passing through the
heating-chamber are thoroughly consumed in
the flue *E* by coming in contact with the
heated wall between the heating-chamber and

the flue. The inlet to the flue E through the flues e, located at either side of the chamber, being double, the burning gases and products of combustion are divided, leaving a comparatively free space behind the door to the heating-chamber, thus giving the operator a good chance to manipulate the stock being heated.

The furnace is built of fire-brick, and the upper part is preferably incased in metal plates G, which are held firmly in position by bolts or rods g passing above and through the walls of the furnace. The apron D also consists of a tile made of fire-clay, and is therefore very durable.

15 By the above construction, it will be seen, I am enabled to produce an even temperature throughout the heating-chamber, insuring a uniform heating of the stock, and also that I utilize the greatest possible amount of 20 heat from a given quantity of fuel.

Having thus described my invention, what I claim as new and of my invention, and desire to secure by Letters Patent, is as follows:

1. A heating-furnace having the fire-chamber A and heating-chamber B separated by a bridge-wall, C, having an apron, D, the bottom of the heating-chamber being in combination with the single broad exit-flue, E, located below the said chamber B and communicating with the heating-chamber by two downtakes or diving-flues, e, located near the charging-door and at the side of the heating-chamber, and formed at or in the side walls of the furnace, substantially as and for the purposes described.

2. A heating-furnace having the fire-chamber A and heating-chamber B separated by a bridge-wall, C, having an apron, D, the bottom of the heating-chamber being inclined upward toward the charging-door, in combination with the single broad exit-flue E, located below the said chamber B, and communicating with the heating-chamber by two downtakes or diving-flues, e, located near the charging-door and at the side of the heating-chamber, and formed at or in the side walls of the furnace, substantially as and for the purposes described. 40 45

3. A heating-furnace having the fire-chamber A and heating-chamber B separated by a bridge-wall, C, having an apron, D, the bottom of the heating-chamber being preferably inclined upward toward the charging-door, in combination with the single broad exit-flue, E, located below the said chambers, and 50 55 communicating with the heating-chamber by two downtakes or diving-flues, e, located near the charging-door and at the side of the heating-chamber, and formed at or in the side walls of the furnace, and tunnel F at rear of 60 said heating-furnace, and communicates with stack, substantially as and for the purposes described.

WM. HARTY.
